ANATOMICAL KNEE

Orvin S. Johnson, El Segundo, Calif., assignor
to Northrop Aircraft, Inc., Hawthorne, Calif.,
a corporation of California

Original application July 3, 1948, Serial No.
36,957. Divided and this application April 23,
1951, Serial No. 222,508

6 Claims. (Cl. 3—22)

1

The present invention relates to artificial legs for above-knee amputations, and is a division of my copending application, Serial No. 36,957, filed July 3, 1948, entitled Anatomical Knee and Hydraulic Snubber.

The aforesaid pending application concerns itself primarily with the hydraulic snubber arrangement shown herein, whereby a cushioned braking action is applied on the knee mechanism to check or slightly retard the free forward swinging movement of the lower leg with respect to the upper leg during the walking cycle, so as to simulate the forward swinging rate of the natural leg. The present invention, on the other hand, is directed to the linkage arrangement of the knee, and its primary object is to provide an artificial leg that duplicates the action of the natural leg in a more nearly exact manner than has heretofore been possible.

Locomotion studies of human gaits have established the fact that during each complete walking cycle, the natural knee locks in two separate positions; the first being when the heel strikes the ground at the forward end of the leg swing, and the second being at the rear end of the leg swing, when the weight is momentarily supported on the toes during the push-off phase. Between the first and second locked positions, or while the body is supported on the leg, the knee unlocks and flexes slightly to cushion the shock of impact. A further object of the invention, therefore, is to duplicate this sequence of action, and to provide a mechanism that exerts a cushioned braking action on the knee, tending to lock the same when the heel strikes the ground, and again during the push-off phase when the weight is carried on the toes.

Another object of the present invention is to provide an artificial leg having a new and improved knee joint mechanism that reproduces almost exactly the geometry of the natural knee. Prior knee joints have, for the most, employed simple hinge pivots; but these fail to duplicate the normal knee action because of the fact that the natural knee joint is not a true hinge. Instead, the shape of the femoral condyles, and the nature of their attachment to the tibial condyles are such that the tibia glides posteriorly on the condyles as the knee is flexed, producing a combination of rolling and sliding movements. Such a motion obviously could not take place about one fixed center, and an analysis of the geometry involved reveals the fact that the condyles of the tibia glide

2

along a curved path approximating the contour of the femoral condyles, while the rate of angular displacement of the tibia with respect to the femur varies with the position of the tibial condyles relative to the femoral condyles. As the tibial condyles approach the upper rear end of their curved path, their rate of travel along that path slows down, while the rate of angular displacement of the tibia accelerates.

10 During flexion and extension of the knee, the length of the natural leg changes slightly as a result of the relative sliding movement between the tibial and femoral condyles, and this changing length enters into the pattern of 15 muscular activity and bodily coordination during the walking cycle to produce the smooth, rhythmic motion characteristic of the normal gait. When a single pivot is used at the knee, the leg remains at a constant length for all positions of flexion and extension, and the amputee finds that the foot tends to strike the ground during the swinging phase of the walking cycle, unless compensated for by rolling the hips or by raising slightly on the toes of the other foot. 20 The result of such compensatory movement is a limping gait. The improved knee joint mechanism of the present invention reproduces in the artificial leg the same lengthening and shortening action which takes place in the natural leg, making it possible for the amputee to walk with a symmetrical and natural gait.

Another object of the invention is to provide an artificial leg embodying the features described above, which is, at the same time, extremely simple in construction, smooth and silent in operation, and free from trouble.

40 The foregoing and other objects and advantages of the present invention will become apparent to those skilled in the art upon consideration of the following detailed description of the preferred embodiment thereof, reference being had to the accompanying drawings, wherein:

45 Figure 1 is a perspective view of an artificial leg embodying the principles of the invention; Figure 2 is a partially cutaway side elevational view of the same;

Figure 3 is a front elevation of the leg; 50 Figure 4 is a sectional view through the ankle and foot, showing the manner in which the hydraulic snubber control mechanism is actuated by upward deflection of the toe portion under load;

Figure 5 is a view similar to Figure 4, but showing the manner in which the control mech-

anism is actuated by plantar flexion of the foot; Figure 6 is a sectional view through the ankle and foot, taken along the line 6—6 in Figure 2;

Figure 7 is a sectional view through the hydraulic snubber mechanism, taken substantially along the line 7—7 of Figure 3;

Figure 8 is a sectional view, looking upwardly, through the hydraulic snubber mechanism at 8—8 in Figure 7;

Figure 9 is a side elevational view of the knee mechanism bent to approximately 90°;

Figure 10 is a schematic diagram, showing the manner in which the geometry of the natural knee was derived;

Figure 11 is a side elevational view of another form of the invention embodying a single pivot knee mechanism with a hydraulic snubber for checking the forward swinging movement of the lower leg with respect to the upper; and

Figure 12 is a front elevational view of the same.

Before launching into the detailed description of the construction and operation of the preferred embodiment of my invention, it might be well to describe briefly the preliminary steps which were necessary in order to derive the geometry of the natural knee in flexion; so that the action might be accurately duplicated in the mechanical knee.

The first step of the preliminary investigation was to take a series of X-ray pictures of the natural knee in progressive stages of flexion, using 10° increments from the extended-leg position of 2° hyper-extension, to the fully flexed position of approximately 135°. Vellum tracings of the femur and tibia were then taken from these X-ray pictures, and the tracings used as templates to make up plastic models of the bones and their condyles. These models were then placed on drawing paper in the exact relative positions occupied by the bones in the series of X-ray pictures, and a composite drawing was made, comprising a series of superimposed outlines which were drawn around the models; keeping the femur in a single fixed position, and changing the position and angularity of the tibia. The outlines and relative positions of the femoral and tibial condyles for the fully extended leg condition are shown in broken lines at F and T, respectively, in Figure 10. It will be noted that the tibial condyle has an upwardly curved load-bearing surface, which is separated from the femoral condyle by an appreciable distance. This space is occupied, in the normal knee, by elastic cartilage which provides a cushion between the condyles.

In order to find the centrode of the tibia, which might be defined as the path of the instantaneous center of pure rotation of the tibia as it moves with respect to the femur, it was deemed desirable to treat the problem in terms of the load center, inasmuch as the knee mechanism is essentially a load carrying joint. The load center was assumed to be at some point along a line intersecting the load-bearing surface, and the direction of the load forces was presumed to be substantially perpendicular to the load-bearing surface at its midpoint. While these assumptions were made more or less arbitrarily on what appeared to be logical considerations, they were subsequently borne out by the ultimate results.

The location of the load center line was established by selecting the two points a_0 and b_0 on the tibial condyles at the ends of the load bearing surface. These points were connected by a

line, and the perpendicular bisector c_0 of that line was then constructed. The line c_0 represents the load center line of the tibia for the position of the condyles shown in Figure 10. Points a_1 to a_9 and b_1 to b_9 were then plotted for nine different positions of the tibia, following which, corresponding pairs of points were connected, and perpendicular bisectors c_1 to c_9 were erected. It might be well to explain, at this point, that the nine positions of the tibia giving the above-mentioned points in Figure 10 are not spaced apart in 10° increments, as in the case of the X-ray photographs, but are merely nine arbitrarily selected positions lying on the pattern obtained from the X-ray pictures.

The points of intersection of each of the lines c with its corresponding line a — b , were then connected by a smooth curve C, which might be termed the "centrode curve" of the load center for the tibial condyle. The centrode, itself, is found by plotting the points d_1 to d_9 formed by the intersection of each of the lines c with the preceding line c . Thus, point d_1 represents the intersection of line c_1 with line c_0 ; while d_2 designates the intersection of c_2 with c_1 , and so on. The generally triangular figure D in Figure 10 is the centrode of the tibia, and clearly illustrates the eccentric displacement of the instantaneous center of rotation of the tibia which takes place during flexion of the knee.

Since the center of load line for the tibia glides posteriorly along the centrode curve C, it became evident, from the start, that the pivot axis of a mechanical knee would have to follow the same curved path C, and that the angular position of the lower leg component about the said pivot axis would have to follow the same curved path C, and that the angular position of the lower leg component about the said pivot axis would have to be controlled in some manner as a function of the linear position of the pivot axis along the curve.

Inasmuch as the curve C is non-circular, it was deemed that the pivot axis could best be held to that path by a system of interconnected linkage operating from two fore and aft spaced points on the upper leg component, and that the angularity of the lower leg component might be controlled by a link connected into the first-named linkage.

It was from the foregoing derivation and analysis of the geometry of the natural knee that the anatomical knee of the present invention was developed.

The principles of my invention will best be understood by referring now to Figures 1 to 9, inclusive, wherein the artificial leg representing the preferred embodiment of the invention is designated in its entirety by the reference numeral 28, and is seen to comprise upper and lower leg components 21 and 22, respectively, which are connected together by a knee joint 23 for relative swinging movement. Mounted on the bottom end of the lower leg component 22 is a foot 24 having a hinged toe portion 25. The upper leg component 21 may take any desired form, and in the present instance comprises a suction socket 26 of the type which is adapted to be held on the stump by a slight suction pressure within the socket.

Attached to the bottom of the suction socket 26, and preferably adjustable angularly with respect thereto about a vertical axis, is a base member 38 having laterally spaced side flanges 31 and 32 extending downwardly from opposite sides thereof. A third flange 33 extends downwardly

from the bottom of the member 30 parallel to and spaced a short distance laterally from the flange 31; the two flanges 33 and 31 being drilled to receive a transversely disposed front pivot shaft 34, and the flanges 32 and 31 being drilled to receive a rear pivot shaft 35 which is parallel to the front pivot shaft and spaced rearwardly from and slightly above the latter. The pivots 34 and 35 are the two fore and aft spaced points about which the knee linkage operates to move the lower leg pivot axis along a path corresponding to the centrod curve C of Figure 10.

The lower leg pivot axis, referred to in the claims as the "third pivot," is designated in the drawings by the reference numeral 36. As best shown in Figure 8, the pivot axis 36 extends coaxially through the cylindrical chamber 37 and operating shaft 38 of a hydraulic snubber 40. The hydraulic snubber 40 constitutes the subject matter of my pending application, Serial No. 36,957, and is fully claimed therein. The following description, therefore, is merely for the purpose of explaining the snubber device illustrated in the drawings so that the mechanism of the artificial leg will be clearly comprehended in its entirety, although it will be understood that the hydraulic snubber forms no part of the present invention. The hydraulic snubber 40 comprises a housing 41 which is fixedly mounted on the top end of a tube 42 forming the shank of the lower leg component 22. The lower leg component 22 is preferably, although not necessarily, of the pylon type shown in the drawings, but might take any other desired form. In the case of the pylon construction shown herein, the tube 42, knee 23, and ankle 43 may be enclosed by a cosmetic shell for the sake of improved appearance and to protect the clothes.

Projecting laterally from one end of the housing 41 coaxial with the pivot axis 36 is a stud 44 that forms the pivot connection for one of the links 45 in the knee mechanism; said link being journaled on a bushing 46 which is pressed onto the stud. At the opposite end of the housing 41 and also coaxial with the pivot axis 36 is another stud 47 which projects from the outer face of a cover plate member 50. Stud 47 forms the pivot connection for another link 51 in the knee mechanism, and to this end is provided with a bushing 52. The member 50 is attached to the outer end of housing 41 by a plurality of bolts, and has a cylindrical portion 53 (see Figure 8) projecting into the cylindrical chamber 37. A circumferential groove 54 is cut into the periphery of the cylindrical portion 53, and a rubber O-ring 55 is seated within the groove to seal the clearances between the cylindrical portion 53 and the inner wall of chamber 37. The member 50 is formed with a cylindrical bore 56 which receives the operating shaft 38, and the inner end of the latter is journaled in a bushing 60 which is pressed into a recess 61 in the inner end wall of the housing 41. The outer end of the shaft 38 projects beyond the stud 47 and is serrated at 62 to receive a link 63 in a rigid interconnection. A split ring 64 is seated within a groove 65 in the end of shaft 38 to hold the link 63 in place. An annular channel 66 is formed in the surface of the bore 56, and seated therein is an O-ring 67 which seals the clearances between the shaft 38 and bore 56.

Formed integrally with the member 50 and projecting laterally therefrom to the inner end of the chamber 37 is a wedge-shaped partition member 70 which is shaped to fill the space be-

tween the wall of chamber 37 and the peripheral surface of shaft 38. A cylindrical valve chamber 71 extends into the partition 70 from the inner end thereof, and rotatable within this chamber is a valve plug 72 having a generally cone-shaped port 73 provided therein, the purpose of which will become apparent presently. The valve plug 72 has a stem 74 projecting axially therefrom through an opening in the housing 41, and mounted on the outer end of the stem is an operating arm 75. An O-ring 76 seals the stem 74 against leakage.

Two passageways 80 and 81 are drilled into the valve chamber 71 from opposite sides of the partition 70, and these passageways cooperate with the valve port 73 to provide restricted communication between the two sides of the partition. The cylindrical chamber 37 is filled with hydraulic fluid, which is forced through the passageways in the partition 70 by a vane 82 on the shaft 36. The vane 82 is keyed into the shaft 38 and cooperates with the partition member 70 to divide the chamber 37 into two compartments. As the vane 82 rotates with the shaft 38, fluid is forced from one of the compartments through the passages 80, 81, and valve port 73 into the other compartment. As shown in Figure 7, the valve plug 72 is normally positioned so that the port 73 is fully registered with passageways 80 and 81. When the valve plug 72 is rotated in a clockwise direction, the small end of the valve port 73 passes beyond the opening of passageway 80, thereby stopping the circulation of fluid from one side of the partition to the other. The large end of valve port 73, however, remains in communication with passageway 81 when the valve is closed, with the result that high pressure fluid in line 81 causes the valve plug 72 to be pressed tightly against its seat at the far side of the chamber 71, thereby sealing the valve against leakage. A wiper seal 83 around the edges of vane 82 closes the clearances between the vane and the walls of chamber 37 against leakage.

The construction and arrangement of the linkage in the knee mechanism 23 will best be understood by referring now to Figures 2 and 3, wherein it will be seen that link 63 is connected at its top end by a pivot bolt 86 to one arm 87 of the bell crank 88. The bell crank 88 is journaled on the front pivot shaft 34 between supporting flanges 31 and 33, and has a second arm 89 spaced 180° from arm 87. Arm 87 extends downwardly and rearwardly from pivot 34, while arm 89 extends upwardly and forwardly therefrom, and is connected by a pivot bolt 90 to the front end of a link 91. The rear end of link 91 is connected by a pivot bolt 92 to an arm 93 of a bell crank 94 which is journaled on the rear pivot 35. Another arm 95 of the bell crank 94 extends downwardly and forwardly from the pivot 35 and is connected by a pivot bolt 96 to the top end of link 45.

It will be noted in Figure 3 that the hub of bell crank 94 is quite elongated and extends across the width of the base member 30 from flange 31 to flange 32. Arm 93 is at the left hand end of the bell crank 94, while arm 95 is at the right hand end thereof. Another arm 97 (see Figure 1) extends downwardly and forwardly from the bell crank 94 parallel to arm 95 and of the same length as the latter, but at the same end of the bell crank as arm 93. Arm 97 is connected by a pivot bolt 98 to link 51 which is parallel and equal in length to link 45, and the two laterally spaced

arms 95, 97, and links 45, 51, provide lateral rigidity in the knee structure.

Another arm 99 extends downwardly and rearwardly from the bell crank 94 adjacent the arm 95, and this last-named arm is connected by a pivot bolt 100 to a forwardly extending link 101. The front end of the link 101 is connected by a pivot bolt 102 to an arm 103 which is formed integrally with the housing 41 and extends upwardly and forwardly therefrom.

The linkage system formed by links 45, 51, 63 and 91 and by bell cranks 88 and 94 serves to control the travel of the bottom pivot 36 to a curved path substantially identical to the centre-to-centre curve C shown in Figure 10, while bell crank arm 99 and link 101 serve to stabilize the lower leg about the bottom pivot 36 and to control the angularity of the lower leg to the flexion pattern indicated by the lines c₀—c₉. The particular geometric patterns of Figure 10 are obtained in the mechanical knee 23 by virtue of certain angular relationships and proportional lengths which will now be described.

Reference is had now to Figure 2, which shows the knee 23 in the extended-leg position. In this condition, link 63 is disposed at an angle of approximately 135° to bell crank arm 87, while the other bell crank arm 99 is disposed at an angle of approximately 62° to link 91. Each of these angular relationships is measured as the included angle between intersecting lines drawn through the centers of the pivot connections at the ends of the members involved. Link 91 is at approximately 92° to bell crank arm 88, while the latter is approximately 135° to bell crank arms 95 and 97, respectively. Bell crank arm 99 is approximately 58° to bell crank arm 95, or 167° to arm 93. Link 101 is at approximately 62° to arm 99, and approximately 74½° to a line drawn through the center of pivot bolt 102 and bottom pivot 36. One other angle which enters into the picture is the included angle between the axes of pivots 34, 36 and 35; the said angle being approximately 28°.

The proportional lengths of the several parts are best disclosed by giving the actual dimensions, in inches, of a typical knee designed for a man of average height and bone structure. The center-to-center distance from pivot axis 36 to pivot bolt 36 (i. e., the effective length of link 63) is approximately 3¾". The center-to-center distance from pivot bolt 86 to pivot 34, and from 34 to pivot bolt 90 is 1" and 1", respectively. The distance from the center of pivot bolt 90 to pivot bolt 92 (the effective length of link 91) is approximately 2½". The distance from the center of pivot bolt 92 to the axis of pivot 35 is approximately 1-14", while the distance from the axis of pivot 35 to the center of pivot bolt 96 is approximately 1¼". The distance from the center of pivot 96 to pivot axis 36 (i. e., the effective length of link 45) and from pivot bolt 98 to pivot axis 38 (the effective length of link 51) is approximately 3¼" each. The distance from the axis of pivot 35 to the center of pivot bolt 100 (bell crank arm 99) is approximately 2½"; from the center of pivot bolt 100 to the center of pivot bolt 102 is approximately 3¾"; and from the center of pivot bolt 102 to the pivot axis 36 is approximately 2¾". It should be understood that the actual dimensions given above are not, in themselves, significant, but rather, it is the proportional lengths of the several members with respect to the others that is critical. In the case of a man of shorter than average height, the correct knee action would be obtained by reducing

all of the dimensions by the same proportional amount; while the reverse procedure would be followed, in the case of a man of greater than average height. The angular relationship between the several parts, would, of course, remain the same for all sizes of the knee mechanism.

It might be noted at this point that when the leg is fully extended, as in Figure 2, the axis 36 of the hinge pivot is located posterior to the vertical line of the center of gravity of the body, causing the pivot to go past the centerline as the leg is extended, giving about two degrees of hyperextension, which gives stability to the joint. The knee joint is stopped at this 2° of hyperextension by means of a limit stop bracket 105 which straddles the front edges of flanges 31 and 33. A strip 106 of composition material is attached to the inside face of the bracket 105 and serves as a bumper for the bell crank arm 99 to limit the counterclockwise rotation of the latter.

When the knee is flexed, the rearward swinging movement of the lower leg 22 about the pivot axis 36 causes the arm 103 to swing downwardly and forwardly in a counterclockwise direction (Figure 2), pulling the link 101 forwardly and rocking bell crank 94 in a clockwise direction. Bell crank 94, acting through link 91, rocks the bell crank 88 in a clockwise direction. As the pivot 36 moves downwardly and forwardly with clockwise rotation of bell crank 88, the distance between front pivot 34 and bottom pivot 36 increases at a diminishing rate of change, while the distance from pivot axis 36 to rear pivot 35 decreases at an increasing rate of change. This condition continues until the lower leg component 22 reaches an angle of about 50° to the upper leg component, at which point the pivot bolt 86 passes dead center between pivots 34 and 36. From that point on, the distance from pivot 34 to pivot axis 36 decreases at an increasing rate of change, while the distance between rear pivots 35 and bottom pivot 36 continues to diminish at an accelerated rate of change.

One important detail in the proper functioning of the leg has to do with the application of a cushioned braking action on the knee 23 responsive to plantar flexion of the foot 24, or to upward deflection of the hinged toe portion 25. This braking action gives the same sequence of locking and unlocking at the knee which is obtained in the natural leg during the walking cycle, and also enables the amputee to recover from a fall by restraining the flexion of the knee to a slow, controlled rate when the weight is thrown suddenly on either the heel or toe portion. Still another advantageous feature of the above-mentioned locking action is that it enables the amputee to walk down an inclined surface without having the knee fold up beneath him.

The braking action referred to above is obtained by controlling the valve 72 in the hydraulic snubber 48 with linkage means actuated by the foot 24 and hinged toe portion 25. To this end, the operating lever 75 of the valve 72 is connected by a link 110 to a lever arm 111 which is pivoted at 112 on the snubber housing 41. A push-rod 113 is connected at 114 to the arm 111 and extends downwardly therefrom through the center of the hollow tube 42. The bottom end of the push rod extends through 70 and is slidable within a guide bushing 115 which is pressed into a hole in a circular plate 116 at the bottom end of the tube 42; said plate being held in place by a cap member 120 which is riveted or otherwise suitably fixed to the bottom end of the tube 42.

The cap member 120 has a pair of laterally spaced ears 121 on the bottom end thereof which are drilled and bushed to provide a journal for a transverse tubular shaft 122, forming the hinge pivot for the ankle 43. The ends of the tubular shaft 122 project beyond the ears 121 and are fixedly received within holes in the ends of arms 123 of a saddle member 124. A threaded stud 125 extends downwardly from the bight portion of the saddle 124 through a hole in the foot 24, and is secured by a nut 126.

Projecting forwardly from the front of the cap member 120 at the lower end thereof is a horizontal shelf 130, which is engageable with the top end of a rubber instep bumper 132 that is set into a recess in the top surface of the foot. An upwardly inclined rear shelf 131 projects from the back of member 120 and is engageable with the top end of a rubber heel cushion 133. The two cushions 132 and 133 engage their respective shelves to locate the foot in its normal position, as shown in Figure 2. The instep cushion 132, being rather short, permits only a very limited amount of dorsiflexion of the foot, while the heel cushion 133, being quite long and resilient, permits a greater degree of plantar flexion.

The toe portion 25 is connected to the foot 24 by a transverse hinge 135 which permits the toe to deflect upwardly with respect to the foot. The toe portion 25 is yieldingly held in the extended position shown in Figure 2 by a rubber cushion 136 which is compressed, as shown in Figure 4, when the toe portion is deflected upwardly. Mounted on the back side of the toe portion 25 is a bracket 140 that is connected by a pin 141 to the front end of a turnbuckle link 142; the rear end of said link being connected by a pin 143 to an arm 144 extending downwardly from a cam 145. The cam 145 is journaled on the ankle pivot shaft 122 between the ears 121, and is provided with a lobe 146 which is normally positioned as shown in Figure 2. Bearing downwardly on the peripheral edge of the cam 145 from above is a cam follower, preferably in the form of a roller 150 which is confined within a U-shaped recess 151 in the bottom of a guide member 152. The guide member 152 is screwed onto the bottom end of push rod 113, and is provided on its front and rear sides with flanges portions which slide up and down in vertical ways 153 in the cap member 120. The roller 150 is held downwardly against the periphery of the cam 145 by a compression spring 154 which encircles the push rod 113 and bears downwardly against a spring keeper 155. The roller 150 is confined against axial displacement from the recess 151 by the side walls 156 (see Figure 6) of the cap member 120, which lie closely adjacent the ends of the roller.

When the hinged toe portion 25 is deflected upwardly with respect to the foot, as shown in Figure 4, the turnbuckle link 142 is pushed rearwardly, rocking the cam 145 in a counterclockwise direction. The roller 150 is lifted by the cam lobe 146, pushing the rod 113 upwardly and raising the valve operating lever 75, which closes the valve port 73 with respect to the passageway 80. Flexion of the knee causes the vane 82 to rotate in a clockwise direction, as seen in Figure 7, and this forces hydraulic fluid from the bottom side of the partition 70 to the top side thereof through the passageways 81, 80, and valve port 73. Partial closing of the valve member 72 throttles this flow of hydraulic fluid through the partition member, creating resist-

ance to rotation of the vane 82 and thereby restraining the knee against further flexion. When the weight is removed from the toe portion 25, the resiliency of rubber cushion 136 causes the toe portion to be returned to its initial position, thereby restoring the cam member 145 to the position shown in Figure 2; while the spring 154 urges the push rod 113 downwardly to reopen the valve member 72.

The hydraulic snubber valve 72 is also moved toward the closed position when the foot 24 is deflected to the position of plantar flexion shown in Figure 5. This is the condition which is obtained when the weight is thrown on the heel at the end of the forward swing phase of the leg during the walking cycle. The resistance of the rubber cushion 136 to compression causes the toe portion 25 to be held in its normal position, with the result that the turnbuckle link 142 and cam 145 remain stationary with respect to the foot while the latter is rocked about the ankle pivot 122. As the cam 145 rotates with the foot, the lobe 146 raises the roller 150 and pushes the rod 113 upwardly against the pressure of spring 154, to rotate the valve plug 72 toward the closed position. When the weight is removed from the heel, the resiliency of the compressed heel bumper 133 causes the foot to be returned to its normal position, which has the effect of restoring the valve plug 72 to its normal open position.

It is believed that the construction and operation of the knee mechanism and hydraulic snubber which are embodied in the preferred form of the invention shown in Figures 1 to 10, inclusive, will be clearly understood from the foregoing description.

Another form of the invention, featuring the hydraulic snubber and brake in a single pivot knee, is shown in Figures 11 and 12, to which reference will now be had. In this embodiment, parts having the same functions as those in Figures 1 to 10 have been given the same reference numerals with the suffix "a."

The base member 30a has two laterally spaced, downwardly extending ears 160 and 161 which pass down over opposite ends of the hydraulic snubber housing 41a, which is fixedly mounted on the top end of the lower leg tube 42a. Ear 161 is drilled to receive the stationary stud 44a at one end of the housing 41a, and is rotatable thereon. Ear 160 is drilled coaxial with the hole in the other ear, and receives the serrated, projecting end of the operating shaft 38a of the snubber. The operating shaft 38a is thus held stationary with respect to the upper leg component 21a, while the snubber housing 41a, being rigidly mounted on the upper end of the lower leg component 22a, rotates with the latter. The mechanism in the hydraulic snubber 40a is the same as that shown in Figures 7 and 8, and therefore need not be described in detail again. The control mechanism in the foot for operating the valve of the hydraulic snubber is likewise the same as that shown in Figures 4, 5 and 6, and its operation is also the same. Thus, the hydraulic snubber and the control mechanism for applying a cushioned braking action on the flexion of the knee is adapted for use in a single pivot knee as well as in an anatomical knee of the type shown in Figures 1 to 10.

While I have shown and described in considerable detail what I believe to be the preferred form of my invention, it is to be understood that such details are not restrictive, and that various

changes may be made in the shape and arrangement of the several parts without departing from the broad scope of the invention, as defined in the appended claims.

I claim:

1. In an artificial leg having upper and lower leg components, a knee joint connecting said components together for relative swinging movement, comprising a transverse pivot adjacent the upper end of said lower leg component, link means connected to said upper leg component at fore and aft spaced points thereon, said link means being connected to said pivot and being operative to swing the latter rearwardly and upwardly in a curved, non-circular path from an initial extended-leg position, and other link means interconnecting said first-named link means with said lower leg component for swinging the latter about said pivot to a predetermined angular relationship with respect to said upper leg component for any given position of said pivot along said curved path.

2. In an artificial leg having upper and lower leg components, a knee joint connecting said components together for relative swinging movement, comprising front and rear pivots on said upper leg component which are spaced apart from one another in a fore and aft direction, a third pivot on said lower leg component spaced downwardly from said front and rear pivots, interconnected link means connecting said third pivot with said front and rear pivots, whereby said third pivot is constrained to move rearwardly and upwardly in a curved, non-circular path from an initial extended-leg position, and other link means operatively connected into said first-named link means and attached to said lower leg component at a point spaced from said third pivot, whereby said lower leg component is maintained at a predetermined angular relationship with respect to said upper leg component for any given position of said third pivot along its curved path.

3. In an artificial leg having upper and lower leg components, a knee joint connecting said components together for relative swinging movement, comprising front and rear pivots on said upper leg component which are spaced apart from one another in a fore and aft direction, a third pivot on said lower leg component spaced downwardly from said front and rear pivots, a bell crank journaled on said front pivot, another bell crank journaled on said rear pivot, a link connecting said third pivot to one arm of said first-named bell crank, another link connecting said third pivot to one arm of said last-named bell crank, another link connecting another arm of said first-named bell crank to another arm of said last-named bell crank, said links and bell cranks coacting with one another to constrain the movement of said third pivot to a rearwardly and upwardly curved, non-circular path from an initial extended-leg position, and another link connected to a third arm on one of said bell cranks and to said lower leg component, for maintaining the latter at a predetermined angular relationship with respect to said upper leg component for any given position of said third pivot along its curved path.

4. In an artificial leg having upper and lower leg components, a knee joint connecting said components together for relative swinging movement, comprising front and rear pivots on said upper leg component which are spaced apart from one another in a fore and aft direction, a

third pivot on said lower leg component spaced downwardly from said front and rear pivots, the included angle between said front pivot, third pivot, and rear pivot being approximately 28°, 5 a bell crank journaled on said front pivot and having an arm extending downwardly and rearwardly therefrom, a link connecting said third pivot with said arm, the included angle between said link and said arm being approximately 135°, 10 another bell crank journaled on said rear pivot and having an arm extending downwardly and forwardly therefrom, a link connecting said third pivot with said last named arm, the included angle between said last-named link and said last-named arm being approximately 168°, said first named bell crank having a second arm disposed at 180° to the first-named arm thereof, said last-named bell crank having a second arm extending upwardly and forwardly from the 15 pivot-axis thereof at an angle of approximately 135° to the first arm thereof, a link connecting said second arm of said first-named bell crank with said second arm of said last-named bell crank, said links and said bell cranks coacting with one another to constrain the movement of 20 said third pivot to a rearwardly and upwardly curved, non-circular path corresponding to the centrod curve of the load center, for the tibial condyles of the natural knee, and another link connecting a third arm on one of said bell cranks with said lower leg component at a point spaced from said third pivot, whereby said lower leg component is maintained at a predetermined angular relationship with respect to said upper leg component for any given position of said 25 third pivot along its curved path.

5. In an artificial leg having upper and lower leg components, a knee joint connecting said components together for relative swinging movement, comprising front and rear pivots on said upper leg component which are spaced apart from one another in a fore and aft direction, a third pivot on said lower leg component spaced downwardly from said front and rear pivots, the included angle between said front pivot, third pivot, and rear pivot being approximately 28°, 40 a bell crank journaled on said front pivot and having an arm extending downwardly and rearwardly therefrom, a link connecting said third pivot with said arm, the included angle between said link and said arm being approximately 135°, another bell crank journaled on said rear pivot and having an arm extending downwardly and forwardly therefrom, a link connecting said third pivot with said last named arm, the included angle between said last-named link and said last-named arm being approximately 168°, said first-named bell crank having a second arm disposed at 180° to the first-named arm thereof, said last-named bell crank having a second arm extending upwardly and forwardly from the 45 pivot-axis thereof at an angle of approximately 135° to the first arm thereof, a link connecting said second arm of said first-named bell crank with said second arm of said last-named bell crank, said links and said bell cranks coacting with one another to constrain the movement of said third pivot to a rearwardly and upwardly curved, non-circular path corresponding to the centrod curve of the load center, for the tibial condyles of the natural knee, a third arm extending downwardly and rearwardly from said last-named bell crank at an angle of approximately 58° to the first arm thereof, and a link connecting said third arm with said lower leg 50 component.

55

60

65

component at a point spaced upwardly and forwardly from said third pivot, the included angle between said third arm and said last-named link being approximately 62° , and the included angle between said last-named link and a line drawn through the pivot axis of its connection to said lower leg component and the center of said third pivot being approximately 74° , whereby said lower leg component is constrained to rotate about said third pivot in a manner closely approximating the angular flexion pattern of the tibia in the natural leg.

6. In an artificial leg having upper and lower leg components, a knee joint connecting said components together for relative swinging movement, comprising front and rear pivots on said upper leg component which are spaced apart from one another in a fore and aft direction a distance of approximately $2\frac{1}{8}l$, where l represents a given unit of length, a third pivot on said lower leg component spaced downwardly from said front and rear pivots, the included angle between said front pivot, third pivot, and rear pivot being approximately 28° , a bell crank journaled on said front pivot and having a first arm extending downwardly and rearwardly therefrom, and a second arm at 180° to said first arm, a link connecting said third pivot with said first arm, the included angle between said link and said first arm being approximately 135° , and the center-to-center distance between the pivot connections at the ends of said link being approximately $3\frac{3}{8}l$, another bell crank journaled on said rear pivot and having a first arm extending downwardly and forwardly therefrom, a second arm extending upwardly and forwardly from said rear pivot at approximately 135° to said first arm, and a third arm disposed at approximately 167° to said second arm, a link connecting said third pivot with said first arm on said last-named bell crank, the included angle between said last-named link and said first arm being approximately 168° , and the center-to-

center distance between the pivot connections at the ends of said last-named link being approximately $3\frac{3}{4}l$, a link connecting said second arm of said first-named bell crank with said second arm of said last-named bell crank, the center-to-center distance between the pivot connections at the ends of said last-named link being approximately $2\frac{1}{2}l$, the distance from the center of said front pivot to the centers of the pivot connections at the ends of both the first and second arms of said first-named bell crank being $1l$ and $1l$, respectively, the distances from the center of said rear pivot to the centers of the pivot connections at the ends of said first, second, 15 and third arms of said last-named bell crank being approximately $1\frac{1}{4}l$, $1\frac{1}{4}l$, and $2\frac{3}{16}l$, respectively, said links and said bell cranks coacting with one another to constrain the movement of said third pivot to a rearwardly and upwardly 20 curved, non-circular path corresponding to the centrodome curve of the load center for the tibial condyles of the natural knee, and another link connecting said third arm on said last-named bell crank with said lower leg component at a 25 point spaced upwardly and forwardly from said third pivot, the included angle between said third arm and said last-named link being approximately 62° , and the center-to-center distance between the pivot connections at the ends of said 30 last-named link being approximately $3\frac{3}{8}l$, said last-named link being operative to rotate said lower leg component about said third pivot to a predetermined angular position for each position of said third pivot along said curved path, so as 35 to approximate the angular flexion pattern of the tibia in the natural leg.
